RELIGIOUS TABLE ORNAMENT

Sara Rae Naimon, Milwaukee, Wis.

Application February 1, 1956, Serial No. 39,992

Term of patent 14 years

(Cl. D29—23)

Fig. 1.

Fig. 2.

Fig. 3.

Fig. 4.

Fig. 5.

I claim:

The ornamental design for a religious table ornament, as shown.
